UNITED STATES PATENT OFFICE

152,908

DESIGN FOR A HOUSING FOR A MAGNETIC STIRRER FOR CHEMICAL LABORATORIES OR THE LIKE

Arthur Rosinger, Newark, N. J.

Application May 4, 1946, Serial No. 129,323

Term of patent 3½ years

(Cl. D16—2)

To all whom it may concern:

Be it known that I, Arthur Rosinger, a citizen of the United States and residing at Newark, in the county of Essex and State of New Jersey, have invented a new, original, and ornamental Design for a Housing for a Magnetic Stirrer for Chemical Laboratories, or the like, of which the following is a specification, reference being had to the accompanying drawings, forming a part thereof.

In the drawings:

Fig. 1 is a plan view of a housing for a magnetic stirrer for chemical laboratories or the like, showing my new design;

Fig. 2 is a front view;

Fig. 3 is a right hand end view, the device being in the position shown in Fig. 2; the vertical high post at the left side of it being partly broken away in this view; and

Fig. 4 is an end view from the left side in said position.

The rear is similar to the front shown in Fig. 2, and the bottom is plain.

I claim:

The ornamental design for a housing for a magnetic stirrer for chemical laboratories or the like, as shown and described.

ARTHUR ROSINGER.
